FREDERICK W. HUBER, OF RIVERSIDE, CALIFORNIA

METHOD AND MEANS FOR CEMENTING OIL WELLS

Application filed December 27, 1928. Serial No. 328,715.

This invention relates to improvements in methods for cementing oil wells, and the main object of the invention is to provide a simple, positive and effective method of cementing off a well hole at a perforated portion of the casing for exclusion of intermediate and bottom waters.

Another object of my invention is to provide an improved method for washing out or clearing the perforations, preparatory to cementing off. In making an oil bore it is customary to carry the bore through the superficial formation to a point just above the productive horizon. At this point the so-called "water string" of casing is landed and cemented or otherwise sealed into place which excludes all of the water, penetrated, from the bore. The bore is then carried, at a smaller diameter, into the oil productive zone to the desired depth. Into this bore is inserted the oil string of casing which is perforated opposite the oil zone. In running in the oil string it is inevitable that some of the perforations become clogged with mud. This factor causes a great deal of uncertainty in case it becomes necessary to make repairs for the exclusion of water.

In the oil productive zones there are very often intermediate water sands or depleted oil or gas sands which have become flooded with water; or it not infrequently happens that the bore is carried beyond the oil zones into a lower zone which is water bearing and so-called "bottom water" is encountered.

The exclusion of these two types of water constitutes a most serious problem in oil production. In the art as heretofore practiced it is customary to attempt to seal off intermediate water by the "squeeze method" in which the cement grout is pumped into the bore through tubing passing through a tight head at the top of the casing (at ground level) and suspending this tubing well above the level at which the cementing operation is to be made. The cement is pumped in and fills up the perforated casing for the desired distance. The system is then sealed off by means of the tight head and a high pressure is applied by means of a pump to force the cement through the perforations. As there

is no assurance that the perforations of the casing are all open the cement will be forced out through those which happen to be free, causing the cement grout to take a devious path and travel through and mix with the mud fluid. The applied pressure is not localized but is effective throughout the whole closed system and acts upon the exposed productive sands, forcing into them mud fluid which usually results in an impairment of their productivity.

My method, now to be described, I believe to be an improvement over any method heretofore in use for the exclusion of intermediate water after the oil string has been landed. I provide a positive means for opening and cleaning the perforations and washing the walls of the hole and so introducing the cement grout at the lowest level as to displace upward the fluid in the hole without appreciably mixing the cement grout with it and producing at any desired level and for any distance a substantial sleeve of cement on the outside of the perforated casing and bonded with it and the walls of the hole without subjecting the exposed oil sands to the pressure applied to the cement grout.

The accompanying drawings illustrate apparatus suitable for carrying out my invention and referring thereto:

Fig. 1 is a vertical section of the well hole, with the cleaning and cementing apparatus in place.

Fig. 2 is a vertical section of the piston or swab.

Fig. 3 is a vertical section of the perforated section of a casing, showing the beginning of the cement operation.

Fig. 4 is a view similar to Fig. 3 showing the end of the cementing operation.

Fig. 5 is a vertical section of the cemented portion of the casing after the cement in the casing has been removed by drilling.

As shown in Fig. 1, the apparatus used in carrying out my invention comprises a tube or pipe 1, which is suspended freely in the casing 2, and is connected by pipe 3 to suitable pumping means for supplying liquid for cleaning the perforations or for supplying the cement, as hereinafter set forth, said tubing 1

being provided at its lower end with a piston, 5 swab, or closure member 4, made of rubber or other suitable material which will make and maintain a snug fit with the interior of the perforated casing and be freely movable therein while maintaining a substantially watertight contact. The object of this piston or swab is to localize the applied pressure.

10 In Fig. 2 I show such a suitable piston or swab fastened onto the end of the tubing, but I do not limit myself to this particular design of the piston as many other types of pistons will serve the same purpose.

15 My improved method may be carried out as follows: It will be assumed that the hole walls are covered more or less with a sheath of mud, which is usually the case where the bore has been made with a rotary drill. Below the formation or strata to be sealed off a bridge, indicated at 5, is placed (as is usual in the art and well known) and the tubing, fitted within the piston or swab, is run into the casing and brought to rest just above the bridge. The upper end of the tubing (at ground surface) is connected through a pump to a supply of water. Water is pumped in and the tubing is slowly raised at a volumetric rate lower than the volumetric rate of the pump. This maintains a localized pressure opposite the lower end of the swab or piston and forces open the clogged perforations in the perforated section 2' of the casing, and the velocity of the water impinging on the hole wall cuts away the adhering sheath of mud. This operation may be repeated in an upward and downward direction between the levels to be cemented, as many times as may be deemed necessary. The piston or swab has been found to be a most effective means of cleaning out the perforations opposite the oil sands. In this instance oil or water can be used as the washing fluid.

The washing operation completed, the tubing is brought back into the position shown in Fig. 3 and the cement grout pumped in. As soon as it is known that the cement is leaving the lower end of the tubing (which is readily determined by a number of well known means) the tubing is raised at a volumetric rate lower than the volumetric rate at which the cement is being pumped in and an adequate localized pressure maintained in this manner. The cement passes through the cleared perforations and displaces the fluid in the hole (mud and water) upwardly without appreciably mixing with it. The raising of the tubing is continued to the upper level of the zone to be cemented. The cement remaining in the tubing can then be washed out or displaced by a following column of water while the tubing is raised above the upper level of the cemented zone. The excess of cement can then be circulated out of the bore in the usual manner. The cement remaining

on the inside of casing is drilled out after it has hardened.

Figs. 3 and 4 show the position of the piston or swab in the perforated casing at the beginning of the operation and at the end of the operation. Fig. 5 shows the finished sleeve of cement, indicated at 6, after the cement in the perforated casing has been drilled out.

The above example illustrates average field practice and is typical of most of the operations which have to date been conducted by this method. Many modifications are possible, in all of which, however, the function of the piston is the same. The essential feature of this invention is the use of this piston or swab for cementing off intermediate and bottom waters through the perforated oil string casing substantially as described without imposing the applied pressure on the productive oil sands.

In the operation described the tubing is not packed off at ground surface by a tight head as is done in the oil art, but is suspended freely in the casing, everything but the tubing being at the prevailing atmospheric pressure.

The invention may also be carried out by closing the casing below the perforated section by bridge 4, and above such section by piston 3, fluid cement being passed through the tube by gravity until the space between such closures is filled with cement, and then the upper end of tube 1 may be closed by a plug or valve, and the tube and piston, together with the cement in the tube, may be forced down by the weight thereof, with the addition of applied pressure, if necessary, so as to force the cement through the perforations in the casing.

I claim:

1. The method of cementing oil wells at a perforated portion of a well casing which consists in bridging the well hole below such perforated portion, forming a closure for the well casing adjacent and above the location of bridging, and progressively raising said closure while introducing cementing material between the closure and the bridging, under sufficient pressure to cause such material to be forced out through the perforations in the casing.

2. The method which consists in forming a bridge below a perforated portion of a well casing, introducing into a well casing tubing open at the lower end and provided with a piston fitting in the perforated portion of the casing, forcing cleaning fluid through the tubing into the space between the bridging and said piston and progressively raising the tubing and piston at a volumetric rate which is lower than the volumetric rate at which the cleaning fluid is being supplied.

3. The method which consists in forming a bridge below a perforated portion of a well

casing, introducing into a well casing or tubing, open at its lower end and provided with a piston fitting in the perforated portion of the casing, forcing cementing material through the tubing into the space between the bridging and said piston and progressively raising the tubing and piston at a volumetric rate which is lower than the volumetric rate at which the cementing material is being supplied.

10 In testimony whereof I have hereunto subscribed my name this 10th day of December, 1928.
